G. F. LE BUS

SAND TESTER PUMP

Filed April 27, 1927

UNITED STATES PATENT OFFICE.

GEORGE F. LE BUS, OF ELECTRA, TEXAS.

SAND-TESTER PUMP.

Application filed April 27, 1927. Serial No. 187,043.

This invention relates to a sand tester pump.

An object of the invention is the provision of a device in which no rods or lines are employed for removing sand for testing and in which the drill pipe is substituted for the usual rods employed inside the tubing to operate the pump which is accomplished by raising and lowering the pipe or tubing, thereby causing fluid to flow through the tubing of drill pipe into the tanks.

Another object of the invention is the provision of a pump which will operate in an efficient manner while cutting off the muddy water from above, thus allowing the pumping operation to maintain a suction directly on the sand, thereby eliminating the expensive method of setting pipes and bailing.

A still further object of the invention is the provision of a pump which is adapted to maintain a sufficient suction which removes the mud and water from the sand that has been forced back into the sand by high pressure rotary pumps used in rotary drilling.

This invention will be best understood from a consideration of the following detailed description, in view of the accompanying drawings forming a part of the specification; nevertheless, it is to be understood that the invention is not confined to the disclosure, being susceptible of such changes and modifications which shall define no material departure from the salient features of the invention as expressed in the appended claims.

In the drawings:

Figure 1 is a vertical section of the pump constructed in accordance with the principles of my invention.

Figure 2 is a fragmentary view in vertical section showing the pump in operative position with the valve in the plunger body closed.

Figure 3 is an enlarged vertical section showing the pump in position with the valve in the plunger body maintained in open position.

Figure 4 is a view in perspective of the friction slide employed in connection with the pump.

Figure 5 is a view in perspective of a valve of the plunger body.

Referring more particularly to the drawings, 10 designates a drill stem or pipe connection which has a flange 11 adapted to engage the upper end of an outside tubular body 12 and having threaded connections at 13 with the drill stem. A hollow plunger stem

14 has its upper end threaded internally of the pipe connection 10 and extends downwardly through the outer body member 12 and in close association with a tubular body 15 providing a support for the plunger stem 14 and also provides a connection for a nut 16 which maintains a packer 17 in position, the said packer embracing the member 15.

A nut 18 is threaded onto the external threads of the member 15 and acts as a stop and lift in connection with a shoe 19 which has threaded engagement with the hollow body member 12. The lower end of the shoe is expanded and provides a shoulder which engages the inner end of the body member 12, and is provided with means at its lower end, as shown at 20, to cut off the packer 17 as will presently be described. The packer 17 while the pump is in operation serves to cut off the water and mud from the upper regions of the hole and prevents the water and mud from entering the oil sand when the same is being removed.

A second packer nut 21 is threaded onto the end of the tubular body 15 and has a shoulder at 22 adapted to engage the upper outer end of a packing body or casing 23 and is threaded onto the nut 21 whereby said packing body is supported. The body 23 has a recess to receive a packing 24 which is in close contact with the outer surface of the plunger stem 14. The lower end of the packing body is reduced and threaded to receive the internal threads at the upper end of the lower tubular casing 25. This shell or casing forms a lower stationary part of the pump.

The plunger 26 is threaded on the inner end of the stem 14 and is adapted to be unscrewed as will be presently described. A valve 28 engaging a seat 29 is located in the plunger 26 and is adapted to be opened or closed for controlling the flow of the fluid through the pump.

The valve 28 as shown more particularly in Fig. 5 has a circular portion 30, a conical portion 31 and a stem 32. Upon the circular portion are three vanes 33, 34 and 35 which have their outer edges 36 in engagement with the inner wall of the plunger 26 whereby the circular member 30 is spaced from said walls to permit the passage of fluid from the lower portion of the pump to the upper portion.

A friction slide 37 is provided with lugs 38 adapted to be forced outwardly by means of springs 39 to engage the notches 40 in the inner wall of the plunger 26. Lugs 38 are

located in a diametrically disposed rib 42 formed integrally with a circular body member 41. Upon opposite sides of the rib and between the circular body are provided passages for fluid. A packing 44 is located within the body member 25 and seated within a recess in the lower end of the plunger 26. A plunger packing nut 45 operates to maintain the packing 44 in position and is screwed onto the lower end of the plunger and also aids in maintaining in position the member 46 which has passages 47 to permit the transfer of fluid at this point. This nut has a square opening 48 which receives the valve 10 adjusting member 49 so that when the nut 46 is rotated the member 49 will be revolved and since this member has threaded engagement, as shown at 50, with a nut 51 the member 49 will be elevated or lowered, depending 15 upon the direction of rotation. The nut 46 has an annular flange 52 received within a socket between the lower end of the plunger and the nut 45 whereby the nut 46 may be rotated and maintained in place.

20 The lower end of the adjusting member 49 has a stem 52^a extending downwardly in the body 25 and is threaded to receive a knob 53.

25 A valve casing 54 is threaded into the body member 25 and is partially closed at its upper end by the nut 51, said nut being provided with passages 55 to permit the transfer of fluid. The valve body is provided with a seat 56 adapted to be engaged by the valve 57 which is guided on the stem 52 through a 30 sleeve 58, said sleeve being slidably mounted in a second nut 59 which likewise has a plurality of passages 60 to permit the transfer of fluid. At times the lower end of the sleeve 58 is adapted to rest upon the knob or nut 53.

35 A packing 61 is adapted to be employed on a lower pump body 62 when the hole is shallow; otherwise, the packings 17 and 61 are employed in conjunction when it is necessary to insert the pump into a deeper well. A nut 63 is screwed onto the body 62 for maintaining the body 61 in position. The body 62, as shown at 64, is screwed into the valve body 54 and co-operates with a shoulder 67 on the valve body and the upper end of the tubular casing 62 for maintaining the nut 59 in place. The tubular member 62 is threaded at its lower end for connecting the perforated nipple which is usually employed and through which the oil is adapted to flow to reach the 50 inside of the pump.

55 The operation of my device is as follows: The valve adjusting member 49 is tightened against the valve 57 and this maintains said valve on its seat 56 to exclude mud and water from the pump and drill pipe while the pump is being placed in the hole. The machine or pump is connected to the drill stem 10 and lowered into the well. If the reduced or small hole in the well is shallow then the lower packer 61 is set in the top of the hole;

otherwise, if said hole has sufficient depth the packer 61 is omitted and the packer 17 is employed at the top of the hole after the working barrel has been placed in the hole. At this time the packer 17 being located above 70 the working barrel cuts off all mud and water from above.

The drill pipe 14 is then rotated towards the right and this disconnects a member 23 from the plunger 26 since the threaded connections between these two members is of right hand type. The plunger is then lowered in the working barrel to permit the wrench 46 to slip down over the adjusting stem and be received in the squared opening 80 48 in said wrench. When the drill pipe is rotated this causes rotation of the member 49 which is threaded with a left hand thread, the drill pipe being turned through five or six revolutions which causes the adjusting 85 member 49 to be elevated sufficiently to unseat the valve 57. The pump is now in condition for operation and the drill pipe is raised and lowered to actuate the plunger 26 in the working barrel and this operation is 90 continued sufficiently to obtain a good test on the sand.

95 After the sand has been tested the plunger 26 is lowered to the bottom of the working barrel 25 until the wrench 46 moves over the member 49 when the drill stem is turned to the right, thereby causing the member 49 which has a left hand thread to travel upwardly, thereby pushing the friction slide 37 against the stem 32 of the valve 28, forcing 100 the friction slide out of the notch 40^a and into notch 40, whereby the valve 28 is forced from its seat and maintained in an elevated position. At the same time the knob or nut 53 on the lower end of the adjusting member 49 105 raises valve 57 from its seat 56. This action opens both valves and maintains them open, allowing the fluid to pass out of the drill stem as it is raised out of the hole.

110 At times when it is attempted to raise the drill pipe after the packer has been set in the sand, the packer will stick and resist the removal of the drill pipe. In such a case the drill pipe is lowered until the milling teeth 20 on the member 19 engages the rubber 115 packer 17 whence the drill stem is rotated, causing the milling teeth to cut off the packer and release the pump. In this operation of the milling teeth of the packer, the wrench 6 continues to turn, adjusting the member 49 120 but does not change the upward and downward motion of the member 49 since it has reached its limit of upward movement in the nut 51 and at this time only idly rotates in said nut.

125 I claim:

1. In a sand tester pump, a shell, a plunger in said shell adapted to be reciprocated and provided with a valve seat, a valve adapted to engage the seat, and means adapted to be ro- 130

tated and force the valve and maintain said valve off the seat.

2. In a sand tester pump, a shell, a plunger in said shell adapted to be reciprocated and provided with a valve seat, a valve adapted to engage the seat and means adapted to be rotated and force the valve and maintain said valve off the seat, a valve in the shell, and a seat in the shell adapted to be engaged by 10 the second mentioned valve and located inwardly of the movable plunger.

3. In a sand tester pump, a shell, a plunger in said shell adapted to be reciprocated and provided with a valve seat, a valve adapted 15 to engage the seat and means adapted to force the valve from and maintain said valve off the seat, carried by the shell, and a valve in the shell, and a seat adapted to be engaged by the valve and located in advance of the movable 20 plunger, the second mentioned valve being slidably mounted on the means for controlling the position of the first mentioned valve.

4. In a sand tester pump, a shell, a plunger slidably mounted in the shell, an inner sleeve, 25 said plunger having a threaded connection with the inner sleeve, whereby one direction of rotation of said plunger will release the plunger from the sleeve, a valve for controlling the flow of fluid through the plunger, 30 and a rotatably mounted stem adapted to be moved longitudinally of the shell for maintaining the valve in open position.

5. In a sand tester pump, a shell, a plunger slidably mounted in the shell, an inner sleeve, 35 said plunger having a threaded connection with the inner sleeve, whereby one direction of rotation of said plunger will release the

plunger from the sleeve, a valve for controlling the flow of fluid through the plunger, a rotatably mounted stem adapted to be moved 40 longitudinally of the shell for maintaining the valve in open position, and a valve located in the shell in advance of the plunger and the first mentioned valve.

6. In a sand tester pump, a shell, a plunger 45 slidably mounted in the shell, an inner sleeve, said plunger having a threaded connection with the inner sleeve, whereby one direction of rotation of said plunger will release the plunger from the sleeve, a valve for controlling 50 the flow of fluid through the plunger, a rotatably mounted stem adapted to be moved longitudinally of the shell for maintaining the valve in open position, and a valve located in the shell in advance of the plunger 55 and the first mentioned valve, said stem being located between the valves.

7. In a sand tester pump, a shell, a plunger slidably mounted in the shell, an inner sleeve, 60 said plunger having a threaded connection with the inner sleeve, whereby one direction of rotation of said plunger will release the plunger from the sleeve, a valve for controlling the flow of fluid through the plunger, a rotatably mounted stem adapted to be moved 65 longitudinally of the shell for maintaining the valve in open position, and a valve located in the shell in advance of the plunger and the first mentioned valve, said stem being located between the valves, the second mentioned 70 valve being slidably mounted on the extension of the stem.
